(57) **CLAIM**

The ornamental design for a semiconductor device as shown and described.

DESCRIPTION

FIG. 1 is a first perspective view of a semiconductor device showing our new design;

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The dash-dash broken lines showing of the semiconductor device are included for the purpose of illustrating portions of the semiconductor device and form no part of the claimed design.

The dot-dash broken lines show boundaries of the claimed design and form no part of the claimed design.

1 Claim, 8 Drawing Sheets
